Primary Examiner — Sheryl Lane*Assistant Examiner* — Nicole Shiflet(74) Attorney, Agent, or Firm — Cantor Colburn LLP(57) CLAIM

We claim, the ornamental design for a display screen or portion thereof with graphical user interface, as shown and described.

DESCRIPTION

The FIGURE is a front view of a display screen or portion thereof with graphical user interface showing our new design.

The broken lines showing the display screen or portion thereof and portions of the graphical user interface form no part of the claimed design.

1 Claim, 1 Drawing Sheet---
